UNITED STATES PATENT OFFICE.

ROLLIN L. DRAKE, OF PORT ARTHUR, TEXAS, ASSIGNOR, BY MESNE ASSIGNMENTS, TO
THE TEXAS COMPANY, OF NEW YORK, N. Y., A CORPORATION OF DELAWARE.

GREASE-GUN CARTRIDGE.

Application filed July 28, 1924. Serial No. 728,559.

This invention relates to improvements in dispensing devices for plastic or semi-plastic materials and more particularly has reference to devices for dispensing grease, solid or semi-solid oils and lubricants in general.

The object of my invention is to provide a cartridge or filler containing lubricants which may be inserted bodily into a lubricant ejector. Also it is one of the purposes of the invention to provide a container for lubricants which may be used in the ordinary type of lubricant ejector and which is manufactured of such low priced materials that it may be thrown away after such use.

Further advantages of the invention will be more clearly recognized by referring to the following description and drawings.

Prior to my invention it had been customary to provide grease gun cartridges with comparatively expensive shells from which it was necessary to remove the mass of lubricant into the grease gun barrel. In performing this operation appreciable amounts of lubricant were left upon the inside of the cartridge shell and thus wasted. Furthermore, in transferring lubricant from cartridge to grease gun the hands of the user were more than likely to become soiled by the lubricant and the transfer was, at best, a cumbersome operation.

My invention seeks to overcome these disadvantages by providing a cartridge having a shell which may be slid directly from its shipping case into the barrel of the ordinary type of grease gun so that the lubricant itself does not need to be disturbed.

Referring to the drawings:

Figure 1 is a front elevation partly in section of an empty cartridge shell.

Figure 2 is a side elevation of the same.

Figure 3 is an elevation, partly broken away and partly in section, of a cartridge filled with lubricant in position in its shipping container.

Figure 4 is an elevation, partly broken away and partly in section, of a cartridge filled with lubricant about to slide from its shipping container into a grease gun barrel.

Figure 5 represents an elevation, partly broken away and partly in section, of a cartridge in final position in a grease gun barrel.

Figure 6 represents the same with the lubricant partly ejected.

Referring particularly to Figures 1, 2 and

3, the cartridge shell 1 has a body portion composed of closely woven fiber or metal cloth stitched at the top to a rigid ring 2, preferably of metal. In order to manufacture the article cheaply the fabric is cut into pieces of proper size and then folded and stitched along the edges 3 and 4 to form a sack. When the ring 2 is stitched to the top a receptacle having an outline as shown in Figure 2 is formed, but which assumes a cylindrical shape when filled with lubricant. It will be seen, therefore, that the rigid open top will be of equal diameter to the lubricant filled sack.

A cylindrical container 5 is provided for shipping the lubricant filled cartridge, the container having a diameter slightly greater than that of the cartridge to permit the latter to be placed therein or easily removed when it is to be used. Likewise the length of the container corresponds to the length of the cartridge. A cap 6 is provided for the container 5 to prevent the entry of foreign materials into the open top of the grease cartridge.

In Figures 4, 5 and 6 the usual type of grease gun is shown having a barrel 7, a piston 8 adapted to operate in the barrel in ejecting the lubricant and a piston rod and handle 9 for operating the grease gun. The gun also has a threaded top 10 which is adapted to screw on to the top of the barrel to exclude dirt and serve as a guide for the piston rod 9. A constricted portion 11 having inclined surfaces 12 and an outlet 13 provides for projecting the lubricant into a tube attached to the outlet 13 or as otherwise desired.

The cartridge is formed of such size that when filled with lubricant it will readily slide into the barrel of the grease gun. It is inserted by removing the cap from the container 5 and holding the container over the open barrel of the grease gun so that the cartridge may slide directly into the barrel without intermediate handling. It will be noted that the cartridge is placed in the container 5 with the ring 2 at the top end of the container thus permitting the cartridge to be inserted in the grease gun barrel in its proper position with the rigid open top at the bottom of the barrel. As the cartridge reaches the bottom of the barrel the ring 2 will come in contact with the sides 12 of the constricted portion 11 and

will not permit the further insertion of the cartridge.

A particular advantage of my invention resides in the function of the rigid top of the cartridge while lubricant is being ejected from the grease gun. A natural tendency of the cloth material, of which the body portion of the cartridge is preferably composed, is to slide down into the constricted portion 11 of the grease gun when the lubricant has been partly pressed out of the cartridge, permitting the cloth to partially or completely close the outlet 13. In using my cartridge, however, it will be clear that the ring 2 holds the top of the cartridge open to the full diameter of the cartridge and at the same time prevents the cloth nearest the ring or top from moving toward the outlet 13 along with the lubricant being ejected. By moving the piston 8 to a position corresponding

to the ring 2 practically all of the lubricant in the cartridge can be ejected leaving in the gun only that small amount of lubricant contained in the constricted portion 11. The empty cartridge sack may then be removed from the gun and discarded. 25

What I claim is:

A collapsible cartridge for loading a grease gun having a barrel with a constricted outlet from which the contents may be ejected, comprising a collapsible sack and a rigid ring at the mouth of the sack adapted to enter the barrel of the grease gun, engage the constriction thereof and hold the mouth of the sack open at the constricted end of the grease gun while the contents is being ejected. 30 35

In witness whereof I have hereunto set my hand and seal this 23 day of June, 1924.

ROLLIN L. DRAKE.
